UNITED STATES PATENT OFFICE.

FREDERICK V. D. CRUSER AND CARL C. HAERKAMP, OF OSWEGO, NEW YORK, ASSIGNEES TO THE DIAMOND MATCH COMPANY, OF CHICAGO, ILLINOIS, A CORPORATION OF ILLINOIS.

ELECTROLYTIC CELL.

Application filed January 4, 1923. Serial No. 610,550.

To all whom it may concern:

Be it known that we, FREDERICK V. D. CRUSER, a citizen of the United States, and CARL C. HAERKAMP, a citizen of Germany, both residents of the city of Oswego, in the county of Oswego and State of New York, have invented certain new and useful Improvements in Electrolytic Cells, of which the following is a specification.

10 This invention relates to that class of electrolytic cells wherein the electrolyte is caused to flow directly between and in contact with spaced electrodes, and more especially to cells of the type wherein carbon 15 anodes and base metal cathodes are employed.

The objects of our invention are to provide an electrolytic cell having a large voluminal capacity for electrolyte, and being of such 20 construction that not only is the rapid heating of the contents of the cell precluded but the cooling thereof can be easily effected and controlled as the electrolytic process progresses; to provide a cell having a plurality 25 of electrolytic chambers so constructed and arranged that the maximum effective area of the respective electrodes therein is attained; to provide a unitary integral cathode structure having the merits of simplicity, cheapness and durability, and to provide a construction which enables the efficient use of carbon anodes and permits and facilitates their ready assembly, removal or 30 replacement, as occasion may require.

35 With these objects in view our invention comprises, in an electrolytic cell, novel features of construction and combinations of parts which, in a preferred form, will be hereinafter described, and the scope of the 40 invention then be defined in the claims.

In the drawings—

Figure 1 is a plan of an electrolytic cell embodying the principle of our invention.

Fig. 2 is a transverse vertical section of 45 the cell, on the line 2—2 of Fig. 1.

Figs. 3 and 4 are horizontal sections thereof, on the lines 3—3 and 4—4, respectively, of Fig. 2.

The cell herein illustrated comprises a rectangular vessel of cast iron having internally arranged walls 5 spaced from the outer walls 6 and constituting therewith a plurality of relatively narrow electrolytic chambers 7 in angular relation to each other. The walls 5 are supported above the

bottom 8 of the vessel by legs 9 to afford communication between the electrolytic chambers and the capacious internal chamber 10 encased by the walls 5; the upper ends of said walls being somewhat below 60 the top of the vessel. The outer walls 6 are offset or expanded at their upper ends, as at 11, and centrally of the chamber 10 is a hollow upright body 12, which is preferably connected to the inner walls 5 by 65 supporting ribs 13. This body extends through and slightly below the bottom of the vessel and is divided interiorly into two vertical passages 14, 15 by means of a partition 16 that terminates short of the top 70 of the body.

The structure above described is preferably an integral casting, whereof the inner and outer walls constitute a negative electrode. One of the outer walls is provided 75 with a suitable connection 17 for the negative terminal; another wall is provided adjacent its upper end with an outlet 18 having a plug 19, and a third wall is provided adjacent its lower end with an outlet 20 having a suitable plug 21. The upper outlet permits the ready overflow of the electrolyte from the interior of the vessel, which electrolyte enters the cell through a suitable siphon tube as usual; and the lower outlet facilitates the flushing of the vessel as occasion may require. The electrolyte thus rises within the series of chambers including the larger chamber 10, and also submerges the hollow body 12 within the latter 90 chamber.

One of the depending walls of the body 12 has an inlet 22 to the vertical passage 14, and the other passage 15 contains a vertical stand pipe 23 which opens though an orifice 95 in the base of the body and rises to a plane above the top of the partition. Hence water or other cooling agent introduced by way of the inlet 22 rises within the passage 14 and overflows at the top of the partition 100 into the passage 15 until the latter is filled, thence rising until it overflows and escapes by way of the pipe 23. This pipe permits the confined air as well as the water to escape from the passages, thus allowing the 105 interior of the body to be filled with circulating water which is effective to cool the walls of the body and absorb the excess heat from the surrounding electrolyte.

Within the respective electrolytic cham- 110

bers 7 depend positive electrode members comprising blocks of carbon 24, which terminate above the bottom of the cell and are spaced from the cathodic walls 5, 6 by means of suitably-disposed insulators 25, preferably of hard rubber. The upper ends of the carbon blocks are detachably secured to a generally rectangular supporting frame 26, of metal, preferably by bolts 27 passing through metal plates 28 along the outer sides of the respective blocks, which plates afford substantial bearing members that rest upon supporting pieces 29, preferably of slate, borne by narrow strips of slate 30 resting upon slate slabs 30' seated in the offset portions of the vessel. The open upper end of the cell is closed by means of a cover 31 of non-conducting material, as slate, which cover is embraced by the carbon blocks and is supported on hard rubber studs 32 projecting from the inner sides of the blocks, whereby when the said blocks and their frame are lifted from the vessel, the cover is withdrawn therewith.

25 The frame 26 may be a solid body, but for the sake of lightness and cheapness we prefer to make it of skeleton or spider-like form as shown. This frame is provided with a suitably-disposed connection 33 for the positive terminal.

From the foregoing it will be seen that a cell embodying our invention has capacity for a large volume of electrolyte, the temperature whereof can be easily effected and controlled, thereby preventing the too rapid heating of the contents of the cell during the electrolytic operation, with the result that the liability of destruction of the electrodes by excess heat is materially reduced. It will also be seen that the carbon anode members are rigidly supported in close relation to the adjacent cathode surfaces in such a manner as to avail of the maximum effective area of the electrodes, and that a cell is provided having the further merits of simplicity, cheapness and durability, together with ease of assembly, removal or replacement of the carbon blocks and their associated parts.

It is obvious that the size and capacity of the cell may be increased within wide limits, in which case the frame 26 can be correspondingly enlarged, or constructed in sections, and a plurality of carbon blocks can be detachably supported thereby in a manner to depend, edge to edge, within each of the electrolytic chambers.

Our invention is not limited to the details of construction herein disclosed, as the same may be modified within the principle of the invention and the scope of the appended claims.

We claim—

1. In an electrolytic cell, a metal vessel having a large chamber therein for electrolyte, the walls of the said chamber being

in spaced relation to the adjacent outer walls of the vessel to provide a plurality of relatively narrow electrolytic chambers in angular relation to each other, said chambers having communication with each other and with the interior of the first-named chamber and all said walls being electrically connected with the bottom of the vessel and constituting an electrode of one polarity, in combination with a plurality of electrode members of opposite polarity to the said electrode, and means for supporting the said electrode members within, and in spaced relation to the walls of the said electrolytic chambers.

2. In an electrolytic cell, a metal vessel having a large chamber therein for electrolyte, the walls of the said chamber being in spaced relation to the adjacent outer walls of the tank to provide a plurality of relatively narrow electrolytic chambers in angular relation to each other, said chambers having communication with each other and with the interior of the first-named chamber and all said walls being electrically connected with the bottom of the vessel and constituting an electrode of one polarity, and said vessel also having therein a hollow body for the passage of a circulating cooling medium, in combination with a plurality of electrode members of opposite polarity to the said electrode, and means for supporting the said electrode members within, and in spaced relation to the walls of the said electrolytic chambers.

3. In an electrolytic cell, a metal structure comprising outer walls, a bottom therefor, and inner walls supported in spaced relation to the outer walls to provide a plurality of electrolytic chambers in angular relation to each other, said inner walls being electrically connected with the bottom and constructed to afford communication between the said chambers and the space encompassed by the inner walls, the inner and outer walls forming an electrode of one polarity, in combination with a plurality of electrode members of opposite polarity to the said electrode, and means for supporting the said electrode members within, and in spaced relation to the walls of the electrolytic chambers.

4. In an electrolytic cell, a metal structure comprising outer walls, a bottom therefor, and inner walls supported in spaced relation to the outer walls to provide a plurality of electrolytic chambers in angular relation to each other, said inner walls being electrically connected with the bottom and constructed to afford communication between the said chambers and the space encompassed by the inner walls, the inner and outer walls forming an electrode of one polarity, and said structure comprising also an upstanding inner hollow body rising

from the bottom and adapted to receive a circulating cooling medium, in combination with a plurality of electrode members of opposite polarity to the said electrode, and 5 means for supporting the said electrode members within, and in spaced relation to the walls of the electrolytic chambers.

5. In an electrolytic cell, a unitary metal structure forming an electrode of one polarity, and comprising an outer body, a central body and an intermediate body, said outer body having side walls and a bottom, said central body having a closed chamber rising from the bottom and adapted to receive a 10 cooling medium, and said intermediate body having side walls spaced from the adjacent walls of the outer body and from the bottom of the latter.

6. An electrolytic cell having an upstanding hollow body therein vertically partitioned to provide vertical passages communicating at their upper ends, an inlet for a cooling agent at the lower end of one of said passages, and an outlet from the other passage comprising a stand pipe extending from the bottom of said body to a level 20 above the partition.

7. In an electrolytic cell, a unitary metal structure comprising an outer body, a central body and an intermediate body, said outer body having side walls and a bottom, said intermediate body having side walls 25

spaced from the adjacent walls of the outer body and spaced above the bottom but electrically connected therewith, said inner and side walls constituting an electrode of one polarity, and said central chamber comprising a hollow body rising from the bottom and vertically-partitioned to provide vertical passages communicating at their upper 30 ends, said passages having respectively an inlet and an outlet for a cooling medium.

8. In an electrolytic cell, a metal vessel having therein an enlarged chamber for electrolyte, the walls of the said chamber being in spaced relation to the adjacent outer walls of the vessel to provide a plurality of relatively narrow electrolytic chambers in angular relation to each other, said chambers having communication with each other and with the first-named chamber and all said walls being electrically connected with the bottom of the vessel and constituting an electrode of one polarity, in combination with a plurality of electrode members 45 of opposite polarity to the said electrode, a frame overlying the vessel, and means for detachably securing the upper ends of the said electrode members to the frame and thereby supporting them within, and in 50 spaced relation to the walls of the said electrolytic chambers.

FREDERICK V. D. CRUSER.
CARL C. HAVERKAMP.
